United States Patent Office

Des. 198,235
Patented May 19, 1964

198,235

COMBINED BOTTLE CAP AND OPENER

John Bruce Rander, 129 W. 46th St., New York, N.Y.

Filed Jan. 2, 1962, Ser. No. 68,164

Term of patent 14 years

(Cl. D58—26)

FIG. 1 is a top perspective view of a combined bottle cap and opener, showing my new design; and

FIG. 2 is a bottom perspective view thereof.

I claim:

The ornamental design for a combined bottle cap and opener, as shown.
